(57) **CLAIM**

(**) Term: **14 Years**

The ornamental design for an enclosure for a speaker cable connector, as shown and described.

(21) Appl. No.: **29/118,947**

DESCRIPTION

(22) Filed: **Feb. 17, 2000**

FIG. 1 is a perspective view of an enclosure for a speaker cable connector showing my new design in full lines with the broken lines showing environmental association matter being for illustrative purposes only and forming no part of my design;

(51) LOC (7) Cl. **13-03**

FIG. 2 shows an end view thereof in full lines and environmental association matter in broken lines;

(52) U.S. Cl. **D13/133**

FIG. 3 is an end view thereof shown in full lines and environmental association matter in broken lines; and

(58) Field of Search D13/133, 184;

FIG. 4 is a side view thereof shown in full lines and environmental association matter in broken lines with the opposite side being a mirror image thereof; and,

439/687, 696, 731, 717; 174/72 C, 84 R,
88 R

FIG. 5 is a top view thereof shown in full lines and environmental association matter in broken lines, with the bottom view thereof being plain and unornamented.
